COMBUSTION APPARATUS

Clark Scholl, Springfield, Ohio, assignor to The Steel Products Engineering Company, Springfield, Ohio, a corporation of Ohio

Application December 13, 1940, Serial No. 370,047

9 Claims. (Cl. 192—85)

This invention relates to stokers and more particularly to a drive for a stoker of the ram feed type.

It is a principal object of this invention to provide a drive for a stoker of the ram feed type adjustable as to rate of feed in which agitation is afforded for the fuel bed under both high and low rates of feed so that objectionable coke formation will be effectively broken up and a properly regulated and controlled feeding action secured.

It is also an object to provide a simple and effective hydraulic control for a directly driven ram feed stoker adapted to provide positive forward feeding movements of the ram at a maximum and substantially uniform rate such as to effect agitation of the fuel bed and the breaking up of objectionable coke formation at each feeding stroke, and operable to vary the period between operating strokes to thereby adjust the rate of feed of the stoker to a predetermined value, as desired.

It is also an object to provide a stoker of the ram feed type which is provided with a clutch for establishing driving engagement from a power source to actuate the ram in substantially uniform rapid feeding and return strokes to effect agitation of the fuel, and in which an adjustable hydraulic control is provided for controlling the operation of such clutch to effect regulation of the period of time between successive feed strokes, thereby varying the rate of fuel supply.

It is also an object to provide a control for a ram type stoker which is sensitive and easily adjustable to any portion of its range of adjustment and adapted for accurate and precise response to floating pressure controllers for regulating the rate of fuel supply to maintain a predetermined pressure condition within a boiler.

It is a still further object to provide as a separate unit, a relatively inexpensive hydraulic control which may be applied to a regular reduction drive for a ram type stoker with a minimum of change and thus used as optional equipment.

Other objects and advantages will be apparent from the following description, the accompanying drawings, and the appended claims.

In the drawings,

Fig. 1 is a view partially in side elevation and partially in vertical section showing a stoker installation of the present type;

Fig. 2 is a plan view looking down upon the gear case and the hydraulic control mechanism with the top covers removed therefrom, certain

of the parts being shown in section to more clearly disclose the construction thereof;

Fig. 3 is an end elevational view of the gear case with a portion of the wall broken away to show the construction of the valve and clutch operating mechanism;

Fig. 4 is a partial vertical sectional view on the line 4—4 of Fig. 2 showing the manually controlled timing valve;

Fig. 5 is a vertical sectional view through the hydraulic control mechanism on the line 5—5 of Fig. 2;

Fig. 6 is a sectional view of a detail of the hydraulic control mechanism on the line 6—6 of Fig. 2; and

Figs. 7, 8 and 9 are detail sectional views through the cylindrical preselector valve member on the lines 7—7, 8—8 and 9—9 respectively, of Fig. 5.

20 Referring to the drawings which discloses a preferred embodiment of the invention, the hopper for receiving a quantity of solid fuel is shown at 10, of suitable construction for supplying the fuel downwardly and forwardly to the space in

25 front of the ram 11 mounted of reciprocation in the ram guide 12. Upon the return stroke of the ram, a quantity of fuel is deposited in front of its feeding face 13, and upon the forward or feeding stroke of the ram, that fuel is advanced

30 into the retort 14 where it is in proper position to be burned upon the fuel bed. Additional forward feeding members 15 are provided in the retort, if so desired, the retort construction herein shown being merely illustrative. A lever system 16 is preferably mounted within the hopper and provided with suitable agitator arms 17 extending into the hopper, so that upon reciprocating movements of the ram 11, lever 16 will effect agitating movements thereof and cause the

35 smooth and uniform feed of the body of fuel, the arrangement of the arms being such that they act to propel the fuel forwardly and into the space in front of the ram upon the return stroke thereof.

40 The ram may be arranged to move with a relatively rapid forward feeding and return stroke at a high rate of fuel feed, such as to cause an effective agitation of the fuel bed. However if such rate of movement is reduced at lower

45 rates of fuel supply, then the effectiveness of the agitating action is impaired and there is an increased tendency for formation of bodies of coke with consequent loss of uniformity and efficiency of combustion. Thus in the present invention, 50 the ram is arranged to be driven by a direct drive

at substantially uniform and relatively rapid forward and return strokes under all rates of stoking, the variation in the rate of fuel supply being secured by providing a variable hydraulic control for establishing predetermined selected time intervals between successive cycles of ram operation. It is preferable to provide for such rapid movement of the ram on the return as well as on the forward stroke since better feeding within the hopper is found to take place where the return movement of the ram occurs rapidly. And preferably the ram is arranged to be directly driven by a crank which gives the desired smooth regulated action of the ram throughout its cycle of movement, the crank being clutch connected under timed hydraulic control, with the source of power.

The ram is arranged to be directly driven from an eccentric crank 23, by means of a connecting rod 21 suitably attached to the transverse pin 22 within the body of the ram. The eccentric crank is preferably formed of separate elements, such as the top crank member 23, and the lower crank member 24, crank 23 being keyed to its drive shaft 25 to effect positive driving relation of the crank. The bearing bracket 26 supported from the lower end of the ram casing provides for mounting shaft 27 about which the lower crank 24 rotates.

The drive shaft 25 projects downwardly from the lower end of a gear case 30 on the top of which is mounted a drive motor 31, preferably an electric motor, which has a V-belt pulley drive 32 for effecting operation of a larger driven pulley 33 carried by driven shaft 34 extending transversely through the gear case. The motor also is preferably directly connected to blower 36 to effect operation thereof for the supply of combustion air through air conduit 37 into the retort.

Attached to the rear side of the gear case 30 by suitable bolts and in closely spaced relation thereto is the hydraulic control unit 40; in order to provide a drive for such unit, a separate pulley on driven shaft 34 is arranged with a V-belt drive 41 to drive shaft 42, which shaft extends into the casing of the hydraulic unit.

Referring first to the mechanical drive for the ram, as shown in Fig. 2 driven shaft 34 is suitably journaled at 50 in the gear casing 30, and is provided at its inner end with a multiple disk clutch member 51. The mechanism includes a slidable clutch collar 52 spline mounted upon a driven member 53 which is directly connected with shaft 54, suitably journaled in the casing as shown at 55. Means are provided for shifting the clutch collar to effect engagement and disengagement of the clutch comprising, as shown in Fig. 3, a yoke 57 for engaging the opposite sides of the collar, such yoke being carried by a shaft 58 rotatably supported in the wall of the casing so that upon rotation, the yoke 57 will effect the shifting of the clutch collar in one direction or the other. This clutch actuating shaft 58 extends outwardly from the gear casing and into the casing of the hydraulic unit 40.

A worm 60 is formed upon shaft 54 and is adapted to engage a worm wheel 61 mounted upon one end of a countershaft 62, the latter being suitably journaled in the walls of the gear casing 30. Shaft 62 also carries a worm 63 which has driving engagement with a larger worm wheel 64, which is keyed to the main drive shaft 25, suitably journaled in the casing and extending downwardly to the eccentric crank for operating the ram. Thus the relatively high speed

shaft 34 is adapted to drive through a double worm gear reduction, substantially reducing the speed of rotation of worm gear 64 and the shaft 25, and correspondingly increasing the power. Also it will be clear that for each revolution of worm wheel 64, the ram makes one complete cycle of movement, including a forward and a reverse stroke.

Worm gear 64 carries an upwardly extending pin 65 on its upper face and outwardly toward the periphery thereof. This pin is adapted to engage with a pin 66 carried by lever arm 68, at a predetermined point in the rotation of worm wheel 64, causing the rocking of lever arm 68 about its supporting shaft 69, this action taking place at a predetermined point in the cycle of movement of the ram, preferably at substantially the point where the forward feeding stroke of the ram is completed, and the ram is about to begin a return stroke. In this position, the body of the ram cuts off communication between the retort and the hopper, avoiding objectionable backing up of the smoke or the fire into the latter. Shaft 69 likewise extends from the gear case 30 into the hydraulic unit 40, and provides for the control of the operation of that unit.

Referring now to the hydraulic unit and more particularly to Figs. 5 through 8, the unit 40 comprises a closed and sealed casing forming a reservoir for receiving a quantity of hydraulic actuating fluid. The drive 41 provides for continuous rotation of shaft 42, this shaft being provided with a fluid pump 70, preferably in the form of a gear pump having communication with the interior of the reservoir and providing for subjecting the fluid to pressure. Supply passage 72 communicates with the discharge side of the pump, the fluid under pressure being supplied through suitably extended and interconnecting passages into a valve chamber 73. Preferably suitable pressure relief mechanism is associated with the conduit to provide for relief of pressure therein when it has attained a predetermined desired value, or, when the cylinder or cylinders in communication with the pump have been filled and their pistons moved to their limits the pump will discharge through the relief valve, the continuously operating pump mechanism thus providing a maintained source of fluid actuating pressure.

A control valve 75 is located in valve chamber 73, and is provided with lands 76 and 77, the pressure supply conduit 72 leading to the space between such lands.

Lands 76 and 77 control respectively the supply of fluid pressure into conduits 78 and 79, depending upon the position which they occupy. A manual preselector valve 80 further controls the passage of fluid through each such conduit, as will be described more in detail hereinafter. In the position in which it is shown, it affords free access for the fluid passing through either conduit 78 or 79. A port 81 opening into the reservoir is located in line with conduit 78 and in position to be controlled by preselector valve 80 as will be hereinafter described. Conduits 78 and 79 lead into a clutch operating cylinder 85, and provide for supplying fluid pressure selectively to one side or the other of the clutch operating piston 86 mounted therein. The piston rod 87 carries a roller 88 at the end thereof, this roller being engaged on opposite sides by downwardly projecting fingers 89 of a lever arm 90 which is fastened to the clutch operating shaft 58. Thus it will be apparent that the supply of pressure fluid through conduits 78 to one side of piston 86 will effect

movement thereof to the right as shown in Fig. 5, and in the direction to cause engagement of the clutch 51, starting operation of the crank and causing an operating movement of the ram. Conversely, supply of pressure fluid through conduit 79 to the opposite side of piston 86 will effect movement thereof to the left, resulting in disengagement of clutch 51 and the termination of movement of the crank and of the ram. An adjustable stop member 92 is preferably provided within the cylinder 85, to prevent excessive movement of the piston to the right beyond that movement necessary to effect proper engagement of the clutch plates.

Land 76 likewise controls communication with a pressure supply conduit 95 which leads through a check valve 96 and connecting conduit 97 into the timing cylinder 100. Timing piston 101 within cylinder 100 is loosely mounted upon the shaft of valve member 75, being normally spring pressed toward the left under the action of compression spring 102. A pin 103 extends through shaft 75 and is adapted to be engaged by the piston in its movement under the action of spring 102 to cause movement of the control valve to the left as shown in Fig. 5. The space to the rear or at the right-hand side of piston 101 is at all times maintained at a normal pressure by reason of its being open to the interior of the reservoir through permanently open aperture 105.

The shaft of the control valve 75 extends through the end cap of cylinder 100 and at its outer end carries a roller 106. This roller engages the opposite sides of a slotted lever arm 107 which is pinned to shaft 69. Shaft 69 also has fastened thereto in predetermined position by means of a key and a set-screw 108 a second lever arm 109 which is bored to receive within its lower end a plunger 110. Plunger 110 is slotted at its lower end for carrying a roller 111 which is adapted to ride on the faces of overcenter cam 112 fixed to the casing. Plunger 110 is normally urged downwardly by means of compression spring 113. Thus in response to turning movement of shaft 69, a corresponding movement is imparted to lever arms 107 and 109, the resiliently urged roller 111 cooperating with cam 112 to cause further compression of spring 113 until the roller has passed over the center of the cam at which time the pressure exerted by the spring causes the roller to roll down the opposite face of the cam. This arrangement provides a positive and quick acting completion of the movement of such parts in either direction after passing the center point avoiding possibility of the valve stopping in a neutral position. Movement of lever arm 107 results in an axial movement of roller 106 and the control valve 75 from one of its positions to the other, movement of the valve to the right being limited by engagement of stop pin 114 with the cylinder cap.

In order to provide for the controlled timing of the escape of fluid from the timing cylinder 100, a leak passage 115 is provided in communication therewith, and leading to a needle valve 116. This valve is provided with an upwardly extending valve stem 117 which projects through the top wall of the housing 40 where it receives an adjustable member 118 providing for the setting of the valve to adjust the rate of escape of pressure fluid from chamber 100 either manually or under the action of floating pressure regulators. The member is preferably so arranged that it provides for variation over the entire range

from practically no time delay up to the maximum desired in an infinite number of steps and with a movement of only about 90°, thereby affording a sensitive, precise, and easily operated control. Such escape takes place through passage 119, back into the reservoir, the setting of the needle valve determining the length of time that is required for the timing piston 101 to move to the left far enough to cause roller 111 to pass over the center of cam 112.

The operation of this construction is as follows. With the drive motor in operation, driven shaft 34 is rotated but the driving connection for the eccentric crank for operation of the ram is interrupted at clutch 51, such clutch being in disengaged position. Operation of gear pump 70 produces an operating pressure in the hydraulic system, this pressure being supplied into conduit 72. In the position assumed, valve rod 75 is moved to its left-hand position in which land 77 cuts off communication with conduit 79, while land 76 establishes the supply of fluid pressure into both conduit 78 and 95. Accordingly fluid pressure is supplied into both the clutch actuating cylinder 85 and timing cylinder 100. Supply of fluid to the latter causes movement of piston 101 to the right, to compress spring 102, and as the spring is compressed, the pressure in both said cylinders correspondingly rises. Cylinder 100 has a greater effective area subject to the pressure than does cylinder 85, and the arrangement is preferably such that piston 101 moves substantially to its extreme right-hand position before sufficient pressure is available to effect movement of piston 86 to the right to cause engagement of the clutch. Piston 86 thus moves after substantially the maximum desired pressure has been established in the timing cylinder 100, and in moving effects engagement of the drive clutch 51, in the manner hereinabove described.

Upon engagement of the drive clutch, power is transmitted from shaft 34 through the double worm reduction gear and into the shaft 25 which in turn effects rotation of the crank and causes movement of the ram to take place in a cycle of movement.

Such movement continues until the cycle is substantially completed, at which time pin 65 has completed a revolution with worm wheel 64, and comes into position to engage and move pin 66 and its accompanying lever 68 and control shaft 69. Such movement of shaft 69 is in the direction to cause shifting of the valve rod 75 to the right, and into the position shown in Fig. 5, such motion being accomplished quickly and positively as a result of the spring detent construction described above.

In such position, further supply of pressure fluid into conduits 78 and 95 is terminated, and the fluid is supplied through conduit 79 into the clutch actuating cylinder at the right of piston 86. This causes an opposite movement of piston 86 and thus results in positive disengagement of the clutch, interrupting the driving connections, and leaving the ram in a position substantially at the end of a feed stroke. It will be understood that sufficient overrun of pin 65 occurs so that the corresponding pin 66 can be reset without interference therefrom, as will be described hereinafter.

Fluid upon the left-hand side of piston 86 is discharged back into the reservoir through conduit 78 and the pressure neutralizing opening

105. However the fluid contained in the timing cylinder 100 is not allowed to escape through the same passage, by reason of the seating of check valve 93. Such fluid is permitted to escape at a predetermined rate past needle valve 116, and through the outlet port 119 into the reservoir. As the fluid gradually escapes from the cylinder, spring 102 moves piston 101 to the left, and finally into position where the hub of the piston engages pin 163. At such point, the piston picks up the valve rod 75, and moves the same to the left-hand position, the resilient detent again providing for prompt completion of that movement after passing the mid-point thereof.

Such return of the valve to its initial position resets the pin 66 in the path of pin 65, and again provides for the supply of pressure fluid to build up the pressure within the timing cylinder, and to supply pressure to the clutch actuating cylinder in the direction to effect clutch engagement. As will be obvious, the adjustment of the needle valve 116 by manipulation of control member 118 which is accessible upon the outside of the casing will provide for predetermining the time required for this movement of the piston to take place, thereby varying the length of time which elapses between successive strokes of the ram. During the course of each stroke however, and after the commencement thereof, the stroke continues at a proper, and preferably relatively rapid rate, such as to provide for feeding at the maximum rate with continuous operation, and likewise to provide for imparting agitation to the fuel bed with resultant breaking up of objectionable coke formation. And it will be clear that such predetermined feeding rate continues regardless of the setting of the manual control member 118, as no matter how slow the over-all rate of fuel supply, as measured in terms of the periods between successive feeding strokes, the stroke itself is maintained substantially uniform and at a relatively rapid rate.

In some cases it is found desirable to provide for continuous ram movements, and to dispense with the regulating features as above described. Likewise under some circumstances it is desirable to provide for maintaining the ram in non-operative position, with the clutch in disengaged condition. For this purpose the preselector valve 80 is provided, and is arranged to have a plurality of manually selective positions for securing these results. Thus the valve as shown is provided with a port 125 which extends diametrically therethrough, and is also provided with a communicating right-angularly arranged port 126, both such ports being in alignment with supply conduit 78. A pair of intersecting conduits 127 and 128 extend through the valve at right angles to each other in line with conduit 79. The valve is likewise provided with a surface slot 129 extending longitudinally thereof and in the zone of conduit 78. The valve is still further provided with a single through passage 130 located to the left of passages 125 and 126, and in position to establish communication through conduit 78 when the valve member is withdrawn to its right-hand position.

In the position of the parts as shown in Fig. 5, continuous communication through valve 80 is provided by means of ports 125 and 128, so that the timed and regulated action of the control proceeds in the manner above set forth. When however valve 80 is turned through an arc of 90°, supply of pressure fluid through conduit 78 is cut off and in this position, passage 126 is in

alignment with conduit 78 and passage 125 establishes communication with port 81 so that fluid on the left-hand side of piston 86 may be discharged back into the reservoir. Fluid is supplied through passage 127 and conduit 79 to the clutch cylinder to cause movement thereof to the left to effect disengagement of the clutch. Thus in such 90° position of the preselector valve, supply of pressure fluid to cause clutch engagement is permanently cut off, and pressure is supplied to actuate piston 86 to the left, thus leaving the clutch continuously in disengaged position.

If selector valve 80 is withdrawn axially from the position shown in Fig. 5 to such point that passage 130 is in alignment with conduit 78, then the slot 129 will provide for discharge of fluid from the right-hand side of piston 86 back into the reservoir, while pressure fluid is prevented from flowing into that side of the cylinder. During the time that valve rod 75 is in its left-hand position, pressure fluid can be supplied through conduit 78 into clutch actuating cylinder 85 in the direction to effect movement of piston 86 to the right, with consequent engagement of the clutch member. At the same time, pressure is supplied into timing cylinder 100, and upon completion of each cycle of operation of the ram, valve rod 75 will be returned to its right-hand position thereby cutting off temporarily the supply of pressure into cylinder 85. The clutch having been engaged however will remain in driving engagement even in the absence of continuous pressure being made effective in cylinder 85, and hence the driving connection will be maintained. From time to time, as the pressure in the timing cylinder falls sufficiently, the valve rod 75 will be actuated to again restore the pressure conditions within both the clutch cylinder and the timing cylinder, thus providing for effecting a continuous and maintained driving engagement.

A weighted member 132 is preferably mounted upon the outer end of the valve rod 80 and is arranged to be received in notches 133 suitably formed for receiving the rod in its several positions of adjustment. It is found that a preselector valve of this construction is especially desirable since it is simple and easy to operate, and further adapts itself quite readily to automatic actuation under the action of floating pressure controllers responsive to steam pressure, or the like. The infinite number of variations in feeding rate attainable with the present control and the securing of such variation within the limits of adjusting movement of the control member of about 90°, make it especially desirable for use with such floating pressure regulators. And it will also be clear that the present control may be arranged for use as optional equipment with a gear and clutch drive for the ram of standard construction so that with only minor changes, the drive may be constructed and installed for use either with or without the hydraulic control mechanism.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A hydraulic feed control adapted for controlling the operation of a clutch in the drive of a ram type stoker to provide for regulating the time intervals between successive operations of the ram

comprising a source of fluid pressure, valve means for controlling the application of said source of fluid pressure, a clutch actuating cylinder and a timing cylinder both adapted to be supplied with pressure from said source, means actuated in a predetermined position in the stroke of the ram for operating said valve means to supply pressure fluid to said clutch actuating cylinder to effect disengagement thereof and for terminating supply of pressure fluid to said timing cylinder, a leakage valve in said timing cylinder controlling the rate at which fluid is discharged therefrom, means for operating said valve means after the discharge of a predetermined quantity of fluid from said timing cylinder to provide for supply of pressure to said clutch actuating cylinder to cause engagement of said clutch and for simultaneously resupplying pressure fluid to said timing cylinder.

2. A hydraulic control providing for regulating time intervals between successive cycles of operation of a clutch controlled device comprising a source of fluid pressure, adjustable valve means for controlling the application of said source of fluid pressure, a clutch actuating cylinder, a timing cylinder, means for supplying fluid under pressure in one position of said valve means to said clutch actuating cylinder to cause engagement thereof, means for also supplying pressure fluid in said position of said valve means to said timing cylinder, means operated at a predetermined point in the operating cycle of said device for actuating said valve means to another position, means operable in said other position of the valve means for supplying fluid under pressure to said clutch actuating cylinder to cause disengagement of said clutch, means also operative in said other position of the valve means for terminating supply of pressure fluid to said timing cylinder, a leakage port for discharging fluid from said timing cylinder at a controlled rate, and means operable after the discharge of a predetermined quantity of fluid from said timing cylinder for restoring said valve means to its first mentioned position.

3. A hydraulic control providing for regulating time intervals between successive cycles of operation of a clutch controlled device comprising a source of fluid pressure, adjustable valve means for controlling the application of said source of fluid pressure, a clutch actuating cylinder, a timing cylinder, means for supplying fluid under pressure in one position of said valve means to said clutch actuating cylinder to cause engagement thereof, means for also supplying pressure fluid in said position of said valve means to said timing cylinder, means operated at a predetermined point in the operating cycle of said device for actuating said valve means to another position, means operable in said other position of the valve means for supplying fluid under pressure to said clutch actuating cylinder to cause disengagement of said clutch, means also operative in said other position of the valve means for terminating supply of pressure fluid to said timing cylinder, a leakage port for discharging fluid from said timing cylinder at a controlled rate, said timing cylinder having a movable member, resilient means for moving said member as the fluid is discharged from said cylinder, and means actuated by said moving member after the discharge of a predetermined quantity of fluid from said timing cylinder for operating said valve means to its first mentioned position.

4. A hydraulic control providing for regulating time intervals between successive cycles of opera-

tion of a clutch controlled device comprising a source of fluid pressure, adjustable valve means for controlling the application of said source of fluid pressure, a clutch actuating cylinder, a timing cylinder, conduits for connecting said source of fluid pressure with said timing cylinder and with said actuating cylinder means controlled in accordance with the position of said device substantially upon completion of a cycle of operation thereof for moving said valve means to a position where fluid is supplied to said clutch actuating cylinder to cause disengagement of the clutch, and means actuated under the control of said timing cylinder for moving said valve member to another position after a predetermined time interval for supplying pressure fluid to said clutch actuating cylinder to effect engagement of said clutch for a subsequent cycle of operation.

5. A hydraulic control providing for regulating time intervals between successive cycles of operation of a clutch controlled device comprising a source of fluid pressure, adjustable valve means for controlling the application of said source of fluid pressure, a clutch actuating cylinder, a timing cylinder, conduits for connecting said source of fluid pressure with said timing cylinder and with said actuating cylinder means controlled in accordance with the position of said device substantially upon completion of a cycle of operation thereof for moving said valve means to a position where fluid is supplied to said clutch actuating cylinder to cause disengagement of the clutch, means actuated under the control of said timing cylinder for moving said valve member to another position after a predetermined time interval for supplying pressure fluid to said clutch actuating cylinder to effect engagement of said clutch for a subsequent cycle of operation, and means operable for adjusting the time interval established by said timing cylinder.

6. A hydraulic control providing for regulating time intervals between successive operations of a clutch controlled device comprising a source of fluid pressure, adjustable valve means for controlling the application of said source of fluid pressure, a clutch actuating cylinder, a timing cylinder, means for supplying fluid under pressure in one position of said valve means to said clutch actuating cylinder to cause engagement thereof, means for also supplying pressure fluid in said position of said valve means to said timing cylinder, means operated in a predetermined position of said controlled device for actuating said valve means to another position, means operable in said other position of the valve means for supplying fluid under pressure to said clutch actuating cylinder to cause disengagement of said clutch, means also operative in said other position of the valve means for terminating supply of pressure fluid to said timing cylinder, a leakage port for discharging fluid from said timing cylinder at a controlled rate, means operable after the discharge of a predetermined quantity of fluid from said timing cylinder for restoring said valve means to its first mentioned position, and additional valve means having a plurality of adjustable positions providing for automatic intermittent operation of said clutch actuating cylinder and for continuous operation thereof in clutch engaged position.

7. A hydraulic control providing for regulating time intervals between successive operations of a clutch controlled device comprising a source of fluid pressure, adjustable valve means for controlling the application of said source of fluid

pressure, a clutch actuating cylinder, a timing cylinder, means for supplying fluid under pressure in one position of said valve means to said clutch actuating cylinder to cause engagement thereof, means for also supplying pressure fluid in said position of said valve means to said timing cylinder, means operated in a predetermined position of said controlled device for actuating said valve means to another position, means operable in said other position of the valve means for supplying fluid under pressure to said clutch actuating cylinder to cause disengagement of said clutch, means also operative in said other position of the valve means for terminating supply of pressure fluid to said timing cylinder, a leakage port for discharging fluid from said timing cylinder at a controlled rate, means operable after the discharge of a predetermined quantity of fluid from said timing cylinder for restoring said valve means to its first mentioned position, and a manually adjustable preselector valve member for controlling the supply of pressure fluid to said clutch actuating cylinder to provide for continuing engagement thereof in one position and for continuing disengagement thereof in another position.

8. A hydraulic control providing for regulating time intervals between successive operations of a clutch controlled device comprising a source of fluid pressure, adjustable valve means for controlling the application of said source of fluid pressure, a clutch actuating cylinder, a timing cylinder, means for supplying fluid under pressure in one position of said valve means to said clutch actuating cylinder to cause engagement thereof, means for also supplying pressure fluid in said position of said valve means to said timing cylinder, means operated in a predetermined position of said controlled device for actuating said valve means to another position, means operable in said other position of the valve means for supplying fluid under pressure to said clutch actuating cylinder to cause disengagement of said clutch, means also operative in said other position of the valve means for terminating sup-

ply of pressure fluid to said timing cylinder, a leakage port for discharging fluid from said timing cylinder at a controlled rate, means operable after the discharge of a predetermined quantity of fluid from said timing cylinder for restoring said valve means to its first mentioned position, and a manually adjustable preselector valve member for controlling the supply of pressure fluid to said clutch actuating cylinder to provide for continuing engagement thereof in one position and for continuing disengagement thereof in another position.

9. A hydraulic control providing for regulating time intervals between successive operations of a clutch controlled device comprising a source of fluid pressure, adjustable valve means for controlling the application of said source of fluid pressure, a clutch actuating cylinder, a timing cylinder, means for supplying fluid pressure in one position of said valve means to said clutch actuating cylinder to cause engagement thereof, means for also supplying fluid pressure in said position of said valve means to said timing cylinder, means operated in a predetermined position of said controlled device for actuating said valve means to another position, means operable in said other position of the valve means for supplying fluid under pressure to said clutch actuating cylinder to cause disengagement of said clutch, means also operative in said other position of the valve means for terminating supply of pressure fluid to said timing cylinder, a leakage port for discharging fluid from said timing cylinder at a controlled rate, means operable after the discharge of a predetermined quantity of fluid from said timing cylinder for restoring said valve means to its first mentioned position, and a manually adjustable preselector valve member having a plurality of positions of adjustment for controlling the supply of pressure fluid to said clutch actuating cylinder to provide for said timed clutch engagement in one position, for continuing engagement in another position, and for continuing disengagement thereof in a third position.

CLARK SCHOLL.
